UNITED STATES PATENT OFFICE.

WILLIAM C. NASH, OF MENASHA, WISCONSIN.

MECHANISM FOR WATERMARKING PAPER WHILE IN A DAMP CONDITION.

1,165,438.

Specification of Letters Patent.

Patented Dec. 28, 1915.

Application filed July 24, 1915. Serial No. 41,668.

To all whom it may concern:

Be it known that I, WILLIAM C. NASH, a citizen of the United States, residing at Menasha, (post-office Neenah,) in the county 5 of Winnebago and State of Wisconsin, have invented a new and useful Mechanism for Watermarking Paper While in a Damp Condition, of which the following is a specification.

10 My invention relates to automatically stamping or impressing upon paper at any convenient point in the length of a paper making machine where the paper is in a suitable moist condition, with a die made 15 from wood, hard rubber or metal, said die being operated by means of compressed air so arranged that the degree of pressure given to the die may be increased or diminished according to the thickness and degree 20 of moisture of the paper to be operated upon. I am aware of the manner of watermarking paper by means of a wire covered roll which is brought into contact with a sheet of paper and produces a displacement 25 of paper stock and showing the usual watermark, and also by means of an elastic type upon a revolving hub, such as was patented by E. R. and O. F. Behrens May 10, 1904, Re-issue No. 12,218, and of a device patented 30 by Edward Illich, May 7, 1907, No. 852,788, for impressing dry paper by means of type arranged around a roll between which and a hard surfaced roll the paper is fed, neither of which devices do I claim.

35 My invention consists of a revolving smooth faced cylinder about ten inches in diameter and eight inches face, the rim of which is formed of thin brass, and as this cylinder contains a plurality of smaller 40 cylinders, in order to prevent confusion in the use of the term "cylinder", this first named one will hereafter be called a drum and the smaller ones cylinders.

45 My invention is shown in the accompanying drawing, in which,—

Figure 1 is an elevation transversely of a paper making machine, showing its side frames, a roll mounted for revolution thereon, and above it, a shaft having a plurality 50 of printing drums mounted thereon. Fig. 2 is an end elevation of one of said printing drums, one of its cylinders being in section and also a part of its rim. Fig. 3 is section 55 partially of said drum, taken parallel with the shaft upon which it is mounted. Fig. 4

is a section transversely of said shaft at a point within the hub of the drum. Fig. 5 is a plan of the face of a mark that is adapted to be used with said printing drum. Fig. 6 is an end view of the type block that is 60 used with said drum, and line of the curve of the surface of the roll with which the type is adapted to be used. Fig. 7 is an end elevation of a modified form of journal box for the upper shaft in Fig. 1. Fig. 8 is a 65 section of the same on the line a , a , of Fig. 7. Fig. 1 is drawn upon a small scale, Figs. 2, 3 and 4, upon a larger one, Figs. 5 and 6 upon a still larger one and Figs. 7 and 8 about half that of Figs. 2, 3 and 4. 70

Similar numerals indicate like parts in the several views.

1, indicates the side frames of a paper making machine; 2, a hard smooth faced roll, which as before remarked may be 75 located at any point in the length of the machine where the moisture in the paper is sufficient for the type to make a clear impression. This roll is mounted upon the shaft 3 and may be formed of any material 80 that will present a hard smooth surface, and be revolved in the direction of the arrow thereon in Fig. 1, by means of its gear wheel 4, from any available source of power.

Above the roll a tubular shaft 5 is mounted 85 in a stationary position, and arranged lengthwise of the shaft are a plurality of printing drums 6. These drums each consists of a hub 7, having arms 8, upon the outer ends of which a thin rim 9 is secured, 90 as with screws 10, and forming a smooth faced cylinder, or drum. The rim is provided with perforations 11, through which the printing type of the mark are to be projected. The drums are each provided with 95 a plurality of cylinders 12, for receiving the expanding element, of which compressed air is preferable. Three cylinders are shown, but no special number is claimed. The cylinders are radially arranged around 100 the bore of the hub of the drum and each one is provided with a piston 13, a square piston rod 14, and a cylinder head 15, which is secured to the open end of the cylinder with bolts or screws 16, and through which 105 head the piston rod is fitted to slide easily. Upon the outer end of each rod 14, a type receiving block 17, is secured with a pin 18. Dovetailed into the block 17, is a type block 19, having the desired letters or design for 110

forming the trade or water mark. The type block may be secured in the dove-tailed type receiving block with a set screw 20, or otherwise. The type block 19 is formed concave upon the type face 21, with a curve corresponding with the curve as near as is practicable, with the curve of the face of the roll 2. This inward curved face in the type is not essential ordinarily, a flat faced type printing satisfactorily unless the roll 2, is very small in diameter, but the face must be of such form, whatever it may be, that it will make an even impression across the type block in order to produce a satisfactory water mark. This is shown in Fig. 6, the line 2, representing the curve of said roll. The printing drums are loosely mounted upon the tubular shaft 5, and are to be revolved by frictional contact with the sheet 20 of paper which is fed in between the roll 2 and drums. The drums are spaced apart upon the shaft and upon a 105 inch paper machine, there may be six or more of the drums. They are held in position lengthwise of the shaft by means of collars 22, having set screws 23. The ends of the hubs 7, are rabbeted upon their outer surface and the bore of the collars correspondingly rabbeted for fitting the hub and forming a joint as near air tight as possible. The drums 6 are shown in Fig. 1 as being in the same position circumferentially of the shaft relative to the perforations 11, but which will not be likely to occur in practice and is not desirable, for the reason that the pressure of the operating element, be it air or steam, will be more uniform if their action is not all at the same instant. The degree of pressure to be given to the type against the sheet of paper can be governed by means of hand screws, as 26. The tubular shaft 5 is provided with shallow grooves 27 and 28, with a space 29 between the grooves, and a small opening 30, through the part 45 29 into the bore of the shaft. These grooves extend to a point outside of the collars. The groove 28, is the one into which the compressed air or steam is exhausted when the drum is being revolved in the direction of the arrow in Fig. 4, and the groove 27 then serves to receive any leakage of air or steam that may take place between the hub and shaft. Should occasion require the changing of the shaft end for end, the groove 27 55 would then become the normal exhaust receiving groove. A perforation 31 is formed at the inner end of each cylinder which is in communication with the aperture 30 as the drum is revolved.

60 The invention has so far been described as being for use with compressed air, but it will be evident that steam may be effectually used in the several cylinders instead of air, although its use would not be desirable on account of the steam and heat

from the exhaust which would necessarily remain in the room, which room is usually none too free from both, steam and heat. Therefore, I consider the use of any expanding element as within the scope of my invention. Compressed air is provided for operating the several type piston rods by means of a pump 32, which may be located at and be driven from any convenient point, it being shown in the present case upon the base of the machine frame and is provided with a pulley 33, which may be driven from a pulley 34 upon the shaft 3. A pipe 35, connects the pump and shaft 5, and is provided with a cock 36, for controlling the flow of air.

The pipe 35 should be provided with a union, as 50, for the easy and quick changing of the shaft 5 for another having a different set of water mark type. The several shafts 5 should be provided with marks and one of the supporting boxes for the shaft with a corresponding mark as X in Fig. 7, that each shaft may be placed in the correct position circumferentially, for the meeting of the apertures 30 and 31 at the exact instant for producing a clear and perfect water mark. The action of the stamping mechanism is to force the type of the desired mark outward through the openings 11, the instant the perforation 31 in the cylinder arrives at the perforation 30, in the pipe. As the distance from the opening 30 to the groove 28 is very short, it follows that immediately after the outward movement of a piston rod the opening 30 will arrive at the groove 28, and the exhaust will occur. A spring 37, is arranged around each piston rod and as soon as the pressure is removed by the action of exhausting, the piston will return to the inward limit of its movement.

A form of box for the support of the shaft 5 is shown in Figs. 7 and 8, which is intended to be used in place of the support shown in Fig. 1. It consists of a stand 38, adapted to be bolted to the lower section of the machine frame 1 in place of the upper section 39 with bolts 40, it having a box 41 arranged to slide in a vertical direction in the dove-tail 42 of the stand. A hand screw 43 is threaded into the arm 44 and is provided with a set collar 45, between which and the box 41 a spring 46 is arranged for pressing downward upon the box. The box is provided with a cap 47, which is hinged to the box at 48, and can be secured closed by means of a pivotal bolt 49. With this box and cap and the arrangement for the vertical adjustment of said boxes and the coiled spring 46, the shaft 5 with a supply of printing drums thereon, can be placed in position and adjusted vertically, quickly and accurately.

Although the device is best adapted and

is described as applicable only to moist paper where it is intended to generally be used, it may be used on a frame separate from a paper making machine, and upon dry and finished stock, but necessarily, will require greater force to be applied for making the impression with possibly inferior results.

Having described my invention, what I claim and desire to secure by Letters Patent, is,—

1. A tubular perforated shaft around which a drum is revoluble, said drum having a cylinder and a piston therein for being acted upon by means of an expansive element deliverable from said shaft, a groove in the shaft along its surface longitudinally thereof into which said expansive element can exhaust after its action upon the piston within said cylinder.

2. A drum having a bore adapted to be mounted upon a shaft for revolution, means for preventing its movement longitudinally of the shaft, a cylinder within the drum having its axis radially arranged from the bore of the drum and a closed end adjacent said bore, a piston in said cylinder, a cylinder head secured over the open end of the cylinder, a piston rod extending from the piston through the cylinder head, a perforation through the closed end of the cylinder from its interior to the bore of the drum, a tubular shaft mounted in a fixed position upon which said drum is mounted and is adapted to be filled with an expansive element, a shallow groove along the outside surface of the shaft, a perforation into the shaft adjacent said groove through the full circumferential portion of the shaft upon that side of the groove upon which the perforation into the cylinder approaches said groove in the revolutions of the drum, and a spring arranged around the piston rod between the piston and cylinder head for returning the piston to the inward limit of its movement after the exhausting of said expansive element through the perforation into said groove.

3. A hard smooth faced roll mounted for revolution upon a suitable frame, a tubular shaft mounted in a fixed position above said roll, a source of an expansive element provided and in communication with said tubular shaft, means for controlling the degree of pressure of said element within the shaft, one or more printing drums mounted loosely upon said shaft, means for securing each drum from movement longitudinally of the shaft, a smooth faced rim around each drum, one or more perforations having the greatest length arranged axially thereof through the face of each drum, one or more cylinders adapted for receiving an expansive element arranged radially within each drum, a piston in each cylinder, a cylinder

head secured over the open end of each cylinder, a piston rod having an angular cross section connected with each piston and extending through the head and outside of the cylinder, a type holder secured upon the outer end of each piston rod, a design or letters representing a trade or water mark for the paper formed of a suitable material for being detachably connected with said type holder and having a printing surface of such form as will produce an even impression of the letters of the mark across the type adapted to be projected through a perforation in the face of the drum and be engaged with a sheet of paper being fed in between said smooth faced roll and type drums, a perforation through the shell of said tubular shaft and into each cylinder for admitting an expansive element thereto and for its exhausting therefrom as each drum is revolved, and a spring around each piston rod between the piston and cylinder head for returning the piston to the inward limit of its movement after each exhaust action.

4. In a device for automatically forming an impression upon paper, a printing drum consisting of a hub adapted to be mounted upon a tubular shaft, a plurality of arms extending from said hub, a thin rim secured upon the outer ends of said arms and forming a cylindrical smooth faced surface around the drum, one or more perforations through the rim having its greatest dimension in the direction of its axial line, one or more cylinders adapted for receiving an expansive element arranged radially within the drum, a piston in each cylinder, a cylinder head secured over the open end of each cylinder, a piston rod having an angular cross section connected with each piston and extending outside of the cylinder and through the head, a type holder secured upon the outer end of each piston rod, a trade or water mark type having its lettered face of such form as will produce an impression of the letters of the mark across the type secured to said type holder and adapted to be projected through one of the aforesaid rim perforations, a tubular shaft upon which said drum is adapted to be loosely mounted and secured from longitudinal movement, means for admitting an expansive element thereto and for its regulation relative to its force, suitable ports for the admission of said expansive element to each cylinder and for its being exhausted therefrom, and a spring around each piston rod between the piston and cylinder head for returning the piston to the inward limit of its movement.

5. In a device for automatically forming an impression upon paper, a printing drum consisting of a hub adapted to be mounted upon a tubular shaft, a plurality of arms extending from said hub a thin rim secured

upon the outer ends of said arms and forming a cylindrical smooth faced surface around the drum, one or more perforations through the rim having its greatest dimension in the direction of its axial line, one or more cylinders adapted for receiving compressed air arranged radially within the drum, a piston in each cylinder, a cylinder head secured over the open end of each cylinder, a piston rod having an angular cross section connected with each piston and extending outside of the cylinder and through the head, a type holder secured upon the outer end of each piston rod, a trade or 15 water mark type having its lettered face of such form as will produce an even impression of the letters of the mark across the

type secured to said type holder and adapted to be projected through one of the aforesaid rim perforations, a tubular shaft upon which said drum is adapted to be loosely mounted and secured from longitudinal movement, means for admitting compressed air thereto and for its regulation relative to its force, suitable ports for the admission 25 of said air to each cylinder from said shaft and for its being exhausted therefrom, and a spring around each piston rod between the piston and cylinder head for returning the piston to the inward limit of its movement. 30
